UNITED STATES PATENT OFFICE.

ALBERT EDWARDS GREENE, OF CHICAGO, ILLINOIS, ASSIGNOR TO AMERICAN ELECTRIC SMELTING AND ENGINEERING COMPANY, OF ST. LOUIS, MISSOURI, A CORPORATION OF MISSOURI.

ELECTRIC FURNACE.

1,070,337.

Specification of Letters Patent.

Patented Aug. 12, 1913.

Application filed November 12, 1909. Serial No. 527,691.

To all whom it may concern:

Be it known that I, ALBERT E. GREENE, a citizen of the United States, residing at Chicago, in the county of Cook and State of Illinois, have invented certain new and useful Improvements in Electric Furnaces, of which the following is a specification.

My invention relates to electric furnaces and metallurgical processes to be practised therewith, whereby the temperature of the material under treatment and the composition of the gas maintained in contact with the material are controlled independently of one another.

15 Broadly the object of the invention is to provide suitable apparatus for the refining of metals, for the extraction of metals from mattes and ores, and for the treatment of materials in general requiring combined 20 heat treatment and chemical action, and the several types of apparatus set forth herein for such ends, all combine a means of electric heating and a control of gas used in the furnace chamber.

25 More specifically this invention consists in means for maintaining electric arcs in proximity to the material as a source of heat, and means for stretching or drawing out such arcs, to obtain uniform heating, and at 30 the same time utilizing a gas to react with the material therein. The result is a control of the gaseous reagents used, or in certain cases of the atmosphere maintained in the furnace, more or less independently of the 35 control of temperature, and thereby making possible reactions otherwise not obtainable, and also increasing the rapidity of treatment and efficiency in general.

In the conversion of metals and mattes by 40 the processes hitherto in general use, the heat is controlled by combustion, or the heat of combustion when excessive may be modified by certain endothermic reagents. These processes are unavoidably inefficient in that 45 it is not practicable to thus control the composition of gas and temperature independently, and the result is a loss of material either by oxidation or a failure to completely extract it by reducing agents, as well 50 as to an inefficient elimination of the impurities. This invention is designed to supply apparatus in which the above losses may be averted.

In the converter process for extracting copper matte, it is impossible to get a satisfactory elimination of iron and sulfur, and at the same time leave the product free from oxids and traces of sulfid. The apparatus of this invention is also applicable to processes by which such difficulties are overcome.

55 In the refining of iron and steel to eliminate phosphorus and sulfur it is desirable, in certain cases, to maintain a high temperature over the surface of the slag while subjecting the material to the action of a gaseous reagent, and this invention provides means therefor.

60 In the extraction of metals from their ores few of the processes now in use accomplish the elimination of a given impurity, or the 65 extraction of a metal, without leaving some of the impurity to be extracted by another process or some of the metal in a by-product, which metal can be saved only by further treatment. For example, the common processes for extracting copper from sulfid ores 70 only partially eliminate the sulfur in the roasting and reduction processes and leave the remainder to be removed in the refining furnace. In the roasting of sulfid ores the 75 elimination of sulfur is incomplete. Moreover the result of the roasting is to convert the larger part of the sulfids into oxids. In the treatment of iron ores containing phosphorus and sulfur these elements are 80 invariably retained in the pig iron, which is the first product of reduction. The problem of reduction of iron pyrite ores has been 85 left for solution until the diminishing supply of oxid ores will create a need for a 90 satisfactory method of getting iron from them.

95 In my copending applications Serial No. 426,334, filed April 10th, 1908, and Serial No. 488,360, filed April 7th, 1909, I have disclosed a metallurgical process suitable for eliminating an impurity such as sulfur by a selective oxidation while the desired metal is retained reduced.

100 It is one of the objects of this invention to provide suitable apparatus for carrying out processes of this nature and such apparatus may be of the two types,—rotary or stirring furnaces and shaft furnaces herein-after described.

105 In one of its forms this invention contem-

plates means for treating the material under the influence of heat produced by electric arcs in rotary and stirring furnaces, and more specifically contemplates the heating of materials in rotary cylinders through which electric arcs are passed.

In the calcining of materials, such as lime, carbon and clays, and in the manufacture of cement, the apparatus of this invention 10 finds an important application and affords an efficient means of accomplishing the desired results.

One of the features of the invention relates to the use of polyphase arcs—either in 15 single combinations between separate pairs of electrodes, or with all the arcs extending to a neutral point or electrode.

Another feature relates to impinging the arc or arcs on the surface of the material, 20 and in certain cases of using the bath as one electrode. Where polyphase current is used the material under treatment may be used as the neutral, or the neutral point may be maintained at a point where the several gas currents which direct the arcs meet.

The invention also provides means for maintaining arcs over the surface of the bath after the preliminary gaseous treatment.

Having considered several of the essential features of this invention broadly, I will now describe these in detail and also several of the embodiments of the invention by reference to the accompanying drawings.

Figure 1 is a vertical central section of a Bessemer converter, modified for electric heating in accordance with this invention. Fig. 2 is a side elevation thereof, partly in section. Fig. 3 is a vertical central section 40 of a copper converter modified in accordance with this invention. Fig. 4 is a side elevation thereof. Fig. 5 is a central vertical section of a modified form of the invention. Fig. 6 is a side elevation of the structure 45 shown in Fig. 5. Figs. 7 and 8 are transverse and longitudinal sections, respectively, of an open hearth furnace embodying this invention. Fig. 9 is a horizontal section of a modification of the invention. Fig. 10 is 50 a vertical section of one end of the furnace shown in Fig. 9. Figs. 11 and 12 are horizontal and vertical sections, respectively, of a further modified form of open hearth furnace. Fig. 13 is an end view of a rotary 55 furnace embodying certain features of this invention. Fig. 14 is a vertical section of a further modified form of rotary converter. Figs. 15 and 16 are vertical, longitudinal sections of different types of rotary cylindrical furnaces embodying this invention. Figs. 17 and 18 are vertical, longitudinal sections of apparatus adapted for the continuous treatment of ores or other material. Fig. 19 is a vertical section of a blast furnace of the type employed for reducing iron

ores, modified in accordance with this invention. Fig. 20 is a vertical section of a type of furnace suitable for reducing copper ores; and Figs. 21 and 22 are vertical sections at right angles to each other of an 70 induction furnace modified in accordance with this invention.

One of the most important embodiments of the invention is in what may be called an electric converter. This type is applicable 75 to the treatment of iron, steel, alloys and mattes, and in certain of its modifications to ores, such as lead and copper ores.

The electric converter of this invention in general embodies a means of heating electrically and a means of forcing gas through 80 the converter in contact with the arc flame, and also in contact with the material to be treated. In the processes now in general use for converting steel and copper, the vessels are large and very expensive, and one of the most important points of advantage 85 of this invention is that it does not necessitate replacing such apparatus by other apparatus of a radically different nature, but 90 on the contrary is a direct modification of the present types of furnaces.

Referring to Figs. 1 and 2, and 3 and 4, two types of electric converters are shown 95 therein, the former adapted more particularly to the conversion of pig iron, and the other more particularly to the conversion of mattes. In Figs. 1 and 2, 1 is the chamber of the converter into which the metal to be converted is placed. Connecting with 100 this chamber 1 are enlarged twy whole 2, and at the upper end of these twy whole entering through the pipe-fitting 4, are the electrodes 3. The electrodes 3 are insulated from the metal work by the insulating bushings 5. 105 Fig. 1 shows also an electrode 6, which may be employed if desired, entering the vessel at a level slightly below that of the metal in the furnace chamber. The blast pipes 7, leading to the twy whole 4, connect with 110 a pipe 12 which leads to the trunnion 9, and in which there is a valve 11 for controlling the pressure of the gas admitted through these twy whole against the top surface of the metal. In the bottom of the converter are 115 shown twy whole 8, which connect with the wind box 10, which is in turn connected to the trunnion 9 through the pipe 12.

Referring to Figs. 3 and 4, the twy whole 21, similar to those in Figs. 1 and 2, 120 connect with the furnace chamber in which the charge of the metal is contained. The mouths of the twy whole are enlarged where they enter the chamber 20, and by tilting 125 the vessel the molten metal can be made to enter the enlarged mouth of the twy whole. When the vessel is so tilted, the arc may be started between the electrode 18 and the metal 19 by moving the electrode into proximity to the metal. The axis of the elec- 130

trode 18 is shown as inclined with respect to the axis of the twyer hole 21, and thereby provides means to start the arc without an excessive length of electrode being required to reach down to the metal bath. The electrode 22 enters the vessel through the insulating bushing 23, and at a height such that it may either be maintained in contact with the metal bath which may thereby serve as one electrode, or it may be maintained above the surface of the bath by tilting the vessel, and thereby provide means for maintaining arcs between the electrodes 18 and 22. The electrodes 18 enter the twyers through the bushings 24 which prevent contact of the electrodes with the elbows 17. The pipe 16 which leads from any suitable source of supply of gas connects with the twyers 21 through the pipe connections 15 and 17. The connection of the pipe 16 through the trunnion 9^a is not shown as any suitable means for accomplishing this may be used. Entering the chamber 20 is shown a twyer 13 which serves to admit gas under pressure at or below the surface of the metal according as the vessel is tilted more or less. This twyer 13 connects with a pipe 14 which leads to a suitable source of gas, and which may or may not be the same source as used for the pipe 16. The exhaust gases leave the vessel through the exhaust opening 26.

Referring to Figs. 5 and 6, there is shown a modified type of electric converter somewhat similar to an open hearth furnace. The metal 122 is contained in the chamber 123, and is subjected to the action of the electric arc extending between the electrode 124 and the metal bath 122 entering through the twyer 25. The length and direction of the arc, as in the figures previously referred to, is controlled by the gas forced in through the pipe 26 around the electrode 124, and the tendency is for the arc to be stretched by the current of gas to the side of the furnace opposite to the electrode 124. On the opposite side of the furnace from the electrode 124 are shown electrodes 27 which serve for maintaining arcs over the surface of the bath where it is desirable to heat the bath without entrance of gas into the furnace chamber. The electrode 27 is so arranged with regard to the bath that it may dip into it if desired, and therefore serve as one means for starting the arc. The spout of the furnace is shown at 29, and one of the doors for admitting material into the furnace is shown at 30. The exhaust gases leave the furnace through the exhaust hole 31. This furnace is preferably of the tilting type.

In Figs. 7 and 8, and 11 and 12, are shown modifications of an open hearth furnace for electric heating of the bath by the use of electric arcs extending over the surface of the metal. These furnaces are arranged so

that the electric heating may be used separately or in conjunction with the usual means of supplying gas to the open hearth furnace. In Figs. 7 and 8 the electrodes are shown at 32 entering the furnace through insulating bushings 33 above the surface of the bath 34. The gas ports are shown at 35 slightly below the level of the air ports 36. The doors 37 serve for the entrance of material into the furnace chamber, and the spout 38 serves for drawing off the metal from the furnace. In Figs. 11 and 12 the electrodes 41 are so located that the arc traverses the chamber above the metal bath in the same direction as the gas from the ports 36 and 35. The pipe 43 leads from a source of gas and connects with the twyers 44, which are located slightly below the level of the electrodes 41, and serve for the admission of suitable gas between the arcs and the bath. 85

In Figs. 9 and 10 are shown two views of a furnace in which the arc is directed by means of a current of gas down against the surface of the bath. The electrodes are shown at 45 entering through the insulating bushings 46, and spreading out inside the furnace in front of the twyer pipes 47 which connect by means of pipes 48 to any suitable source of supply of gas.

Fig. 15 shows a rotary cylinder with the chamber 51 lined with suitable refractory material. The opening 50 to this chamber may be made air tight after the material has been placed in the chamber, and the cylinder is provided with means for rotation on the roller bearings 53. Opening into the chamber 51 are pipes 52, through which enter the electrodes 54 out of contact with the pipes 52. Connecting with the pipes 52, are gas-tight joints 55, which allow the cylinder to rotate independently of said joints. The electrodes 54 enter through insulating bushings 56. The joints 55 are connected by means of valve pipes 57 to any suitable source of gas or suitable exhaust apparatus, 110 as the case may be.

In Fig. 16 is shown a cylinder of similar construction to that in Fig. 15, except that the ends of the cylinder do not rotate with the cylinder body, and are separate from it. 115 In the heads 58 the electrodes 54 are placed at equal distances from each other and around the gas inlet 52. This construction makes possible the use of polyphase currents for blowing the arcs out into the furnace 120 chamber. The arcs may extend from the electrodes 54 at one end of the cylinder to the corresponding electrodes 59 at the opposite ends of the cylinder. Or the arcs may extend from the three electrodes at one end 125 of the cylinder coming together in a common neutral point, and by the use of gas blown through the inlet 52 the arcs may be stretched out into the furnace chamber. The gas pipes 60 serve for the entrance and 130

exit of the gas forced through the cylinder, and these pipes are fitted with valves 61 for the control of the entrance and exit of the gases used in the cylinder.

5 Figs. 13 and 14 show two arrangements of the electrodes in the heads of the cylinders. Fig. 13 shows the location of the electrodes for use of three phase currents, and Fig. 14 shows the arrangement used for 10 blowing a single phase arc away from the electrodes.

In Fig. 17, showing another modification of rotary cylindrical furnaces, 72 is the rotating part of the cylinder. The electrodes 15 73 enter the stationary head 70 through the insulating bushings 74 and are located in any desirable manner for the use of single phase or polyphase current. At the opposite end of the cylinder the head 71 contains 20 electrodes 75 located for maintaining the arcs from the electrodes 73 through the furnace chamber. Through the head 70 at the lower end of the cylinder the gases enter 25 through the pipe 76. The joint 77 connecting therewith, leads from any suitable source of supply of gas, and the twyer 78 which enters the joint 77 may be used for the supply of different gas from that entering through the pipe connecting with 77. 30 At the upper end of the cylinder the gases are removed through the exhaust opening 80. The entrance of material into the cylinder is accomplished from the hopper 81 in combination with the screw 82 and the feed 35 of material into the cylinder may thereby be regulated. The exit of material from the cylinder takes place through the opening 79. The rotation of the cylinder and the mechanical operation in general is carried out by 40 means well known in the art.

In Fig. 18 is shown a further modification of a rotary furnace and a combination of furnaces for utilizing the combustible gas from one chamber by burning it in another 45 chamber to heat the material therein. The cylinder 83 in this figure is similar to that shown in Fig. 17, and connects at its upper end by means of the stationary joint 87 with the cylinder 84. The material enters the 50 cylinder 84 by means of the hopper 81 and screw 82, and passes from the cylinder 84 through the passage 87 into the cylinder 83, and from the cylinder 83 it may pass into 55 any suitable furnace, such as shown at 85 for melting the materials treated, or may be disposed of in any desired manner after leaving the cylinder 83. Entering the cylinder 84 through the head 70 is a nozzle and pipe 86 for the supply of gas to support 60 combustion in the cylinder 84, and by this means to heat the material passing through the cylinder 84. The opening 76 into the cylinder 83, which connects with any suitable source of gas serves for the supply of 65 gas to react with the material in cylinder 83,

while under the influence of electric heat generated from the arcs extending between the electrodes 74. For example, in this cylinder 83 certain elements may be oxidized while the metal desired may be retained in a reduced state. When this takes place at a temperature below the fusion point of the material treated, a final melting and separation of the oxidized and reduced elements may take place in the furnace shown at 85. 70

Figs. 19 and 20 show the method of applying this invention to blast furnaces, the latter showing the type ordinarily used for smelting copper and lead modified according to this invention. 94 is the upper part 80 of the furnace shaft. 91 is the bosh connecting therewith, and 90 is the metal chamber beneath the bosh where the smelting of the material is accomplished. 92 are the enlarged twyers into which the electrodes 93 enter through the bushings 96, which serve to insulate them from the blast pipe connection 97 connecting with the bustle pipe 98. 99 is the tapping spout. The pipe 95 serves for the exit of gases from the furnace. 90

Figs. 21 and 22 show the combination of the features of this invention with a furnace of the induction type. The electrodes are shown at 105 and 106. The electrode 105 enters the furnace chamber through the 95 blast pipe connection 102. 107 is a door for the entrance of material into the furnace chamber. 103 is a pipe for the removal of exhaust gases. 104 is the core, around which the coils 108 are placed. The small 100 channels surrounding these coils are shown at 100. The tapping spout for the furnace is shown at 110. In case it is desired to use the metal as one electrode, the electrode 111 connecting with the metal bath serves as 105 one terminal of the passage of current.

The application of the apparatus and the use of the same for the conversion of pig iron into steel, and for the removal of phosphorus and sulfur will now be described. 110

The apparatus is so constructed that the metal may be blown by air or other suitable oxidizing agent to any desirable point of elimination of carbon, and may subsequently be blown with a reducing gas or a gas of such composition as to remove the undesired elements without oxidation of the metals of the bath which it is desired to retain reduced. For the elimination of phosphorus and sulfur, a basic slag is required to hold these elements after elimination from the metal, and the lining of the vessel must, in such instances, be of the basic character in order to avoid corrosion by the basic slag. Assuming that it is desired to convert impure pig iron into steel according to processes for selective oxidation, the pig iron to be converted is placed into the converter in a molten state. Since the gas used for conversion may not supply sufficient heat in re- 125 130

acting with the impurity in the bath to maintain the desired temperature, the means disclosed in this specification for maintaining long arcs may be resorted to. To start the arc, the vessel may be tilted so that the metallic bath and the electrodes may be brought in proximity to each other, and the arc started in this manner. After starting, the arc may be stretched out by tilting back the vessel while raising the voltage applied to the electrodes as may be required. It may be advantageous in certain cases to use the neutral electrode in contact with the metallic bath to start the arc, and in the case of polyphase arcs being used the neutral electrode may be used to prevent shifting of the neutral point. In starting the arc, the tendency is for the arc to assume the shortest path between the electrode and the bath. By blowing in the gas around the arc, the arc is made to stretch out over the surface of the bath to a point distant from that nearest the electrode. By this means the heat of the arc is communicated to the gas, and simultaneously to the metal or material in the furnace chamber, and to a uniform degree, avoiding thereby extremely high temperatures in limited areas of the bath. In order to hasten the elimination of carbon, the blast of gas may be forced through the bottom twy whole as well as through those through which the electrodes enter. By means of the valve connecting the electrode twy whole to the source of supply of gas, it is possible to regulate the pressure in these latter twy whole, and this is necessary since the pressure required to maintain the static pressure of the bath of metal would be too great for use above the bath. After the carbon has been eliminated as far as desired, the elimination of phosphorus and sulfur may next be accomplished. As it is desirable to eliminate both of these elements in a single slag, it is necessary to keep any oxid of iron or other metals in the bath from being present in this slag. The flux for accomplishing this would preferably consist of lime and fluor spar. The gas employed in the treatment is blown into the furnace chamber around the electrode and carries the arc down over the surface of the bath, making it impinge on the fluxing materials used. This is an important feature of this invention since it enables the treatment of the metal in the presence of a flux with a suitable gas for eliminating the impurities which thereupon pass into the slag.

In certain instances, it may be desirable to maintain the electric discharge over the surface of the bath after the blowing has been stopped for the purpose of eliminating gas absorbed in the metal. In bottom blow converters where it is desired to do this, the bottom blow twy whole may be placed in a portion only of the bottom of a furnace, as shown

in Fig. 3, so that the metal may be held without running into these twy whole after the blast has ceased.

In the operation of the furnaces shown in Figs. 7 to 12, the treatment is quite similar to that described above. The combination of electrodes in the chamber of an open hearth furnace for maintaining an electric arc with the gas ports of that furnace afford means for the treatment of the charge while passing a reducing gas through the furnace, and in this way greatly aiding in the elimination of phosphorus and sulfur from the metal.

Figs. 3 and 4 show a modification of the type of the converter used in converting mattes. This modification is designed for the treatment of copper mattes and mattes in general including nickel. In using this apparatus for converting mattes, it is especially advantageous for the purpose of maintaining the temperature of the large amounts of metal oxidized and held in the slag above the metal bath. By processes of selective oxidation, it is possible in this apparatus to oxidize the sulfur and iron and other undesirable impurities, while retaining the copper or other metal, as for example, nickel in a reduced state. By this means, an attractive method is offered for the separation of nickel from ferro-nickel pig and from nickel mattes. The iron may be oxidized and slagged off in combination with suitable fluxes, while the nickel is retained as metal. In the treatment of mattes, the use of a twy whole located at about the level of the metal is of a special advantage in obtaining contact between the metal and the gas where very large amounts of slag are produced. Tilting the vessel will serve to obtain the desired relation of this twy whole to the level of the metal.

The application of this apparatus in the continuous treatment of ores will now be described.

Apparatus for the continuous treatment of materials may be either in the form of rotary cylindrical furnaces shown in Figs. 15 to 18, or furnaces having other suitable stirring means for getting contact between the gas and the ore under the influence of the arc, or may be of the shaft furnace type with blast connection, shown in Figs. 19 and 20. These furnaces are applicable to the treatment of ores and material in general, but are preferably designed for the treatment of ores according to selective processes. For example, in the treatment of copper sulfid ores, this apparatus affords a means of eliminating the sulfur from such ores in the form of a gas, while obtaining the copper in a reduced state. Similarly, in the treatment of iron ores containing phosphorus and sulfur, this apparatus affords a means of eliminating the phosphorus and

130

sulfur by means of a gas, and leaving the metal in a reduced state. This may not require temperatures high enough to satisfactorily melt the reduced iron, and therefore a suitable melting furnace might well be used in combination with such furnaces for suitably separating the metal and the other elements of the ore, as shown in Fig. 18.

- 10 To make clear the operation of the apparatus, assume that it is desired to treat a copper sulfid ore for the purpose of eliminating the sulfur, and obtaining the copper in a reduced state in a continuous operation.
- 15 Apparatus suitable for this end, is shown in Fig. 18. The ore is fed into the rotary cylinder by means of the hopper and screw. In passing through this cylinder, the ore becomes heated by the combustion of the gas 20 entering from the cylinder next below. Air is blown in to the upper cylinder to burn the combustible gas. The heated material from the upper cylinder enters the lower cylinder, and is there treated under the influence of electric heat generated by the arcs 25 in this lower cylinder and the gas forced in at the lower end of this lower cylinder. This gas accomplishes the elimination of the sulfur and leaves the metallic copper in a reduced state mixed with other elements, 30 such as silica, from which it is necessary to separate the copper. This separation may be accomplished in the furnace 85 situated below the lower cylinder 83, by melting the 35 metal and separating it from the other remaining ingredients of the ore. This is preferably done under the influence of electric heat, and in a furnace in which the atmosphere is of the desired nature, reducing 40 in this instance.
- 45 In the manufacture of cement, this apparatus offers an effective means of accomplishing the results desired, namely,—the elimination of carbon dioxid, and the sintering of the elements required to form cement.
- 50 The types of rotary electric furnaces shown in Figs. 15 and 16, serve for the treatment of materials in a closed chamber which may or may not have gas forced 55 through it to assist in the desired reactions. Such apparatus is suitable, for example, for the calcining of materials like carbon, limestone, clay, etc. The stirring action obtained in these rotary furnaces is an essential 60 feature of the invention. The means for obtaining the stirring action in the material is not limited to rotation of the furnaces, but other suitable means to stir the material, while under the influence of the 65 electric arc may be used. It is understood that the invention is not limited as to the means of accomplishing the stirring action.
- In applying the invention to blast furnaces, the operation of the furnaces of this 70 type is quite similar to the operation in the

above described types. By blowing in the gas around the arc, and making the arc impinge on the material in the smelting chamber of the furnace, efficient melting of the material is thereby accomplished, and 75 the utilization of the hot gases whose composition may be controlled prior to their entrance into the furnace, is effected.

One other embodiment of the invention has been shown in Figs. 21 and 22 in a furnace of the induction type. It is well known that although the induction furnace affords effective means of generating heat in the metal, it does not provide for effectively heating a flux or slag lying on top of the 80 metal. It is the object of this embodiment to combine with the efficient means provided by the induction furnace for heating the metal, the means described herein for heating and treating the slag above the metal. 85

Although having described in detail several of the embodiments of this invention, it is understood that its features may be combined in numerous other ways, and that it is applicable in other types of furnaces than 90 those described.

I claim:

1. In an electric furnace, the combination with a tilting furnace chamber suitable for inclosing material for treatment, of an electrode in the side wall of said chamber above the surface of said material, means for maintaining an electric arc between said electrode and said material, and means for tilting said chamber and thereby bringing 100 said material in proximity to said electrode to start the arc.

2. In an electric furnace, the combination with a tilting furnace chamber suitable for inclosing material for treatment, of an electrode in the side wall of said chamber above the surface of said material, means for maintaining an electric arc between said electrode and said material, and means for passing a current of gas through said chamber and thereby drawing out said arc. 110

3. In an electric furnace, the combination with a furnace chamber suitable for inclosing material for treatment, of electrodes projecting into said chamber from opposite 115 sides thereof, means for successively maintaining an electric arc above the surface of said material between one of said electrodes and said material and between said opposite electrodes, respectively.

4. In an electric furnace, the combination with a furnace chamber suitable for inclosing material for treatment, of an enlarged twyer opening into said chamber above the surface of said material, an electrode within 125 said twyer, and means for maintaining an electric arc between said electrodes and the material under treatment.

5. In an electric furnace, the combination with a furnace chamber suitable for inclos- 130

ing material for treatment, of a plurality of electrodes mounted at one side of said chamber, means for maintaining a polyphase electric discharge from said electrodes to said material, and means for supplying a current of gas for lengthening the arcs produced by said electric discharge.

6. In an electric converter, the combination with a tilting furnace chamber, of an enlarged twyer located above the surface of the

material in said chamber, an electrode in said twyer, and a twyer near the bottom of the chamber at one side thereof.

Signed by me at Washington, D. C., this 12th day of November, 1909.
